Attest

United States Patent Office.

CASPER VAN HOESEN, OF CATSKILL, ASSIGNOR TO HIMSELF, JOHN H. BURTIS, OF BROOKLYN, AND M. W. STAPLES, OF CATSKILL, NEW YORK.

Letters Patent No. 97,995, dated December 14, 1869.

IMPROVEMENT IN SUSPENDERS.

The Schedule referred to in these Letters Patent and making part of the same.

To all whom it may concern:

Be it known that I, CASPER VAN HOESEN, of Catskill, in the county of Greene, and in the State of New York, have invented certain new and useful Improvements in Suspenders and Shoulder-Braces; and do hereby declare that the following is a full, clear, and exact description thereof, reference being had to the accompanying drawings, and to the letters of reference marked thereon, making a part of this specification.

The nature of my invention consists in the construction and arrangement of a metallic, elastic attachment to be used on suspenders, shoulder-braces, or any other place or article where elasticity is required.

In order to enable others skilled in the art to which my invention appertains, to make and use the same, I will now proceed to describe its construction and operation, referring to the annexed drawings, in which—

Figure 1 is a front view of a portion of a suspender with my metallic elastic attachment, and

Figure 3 is a rear or bottom view of the same.

Figure 2 is a view of the spring.

A represents the spring, made of any suitable metal, of flat or slightly oval zigzags, having oblong eyes or loops, B B, formed on each end.

C C represent two portions of ordinary suspender-webbing or tape, each of which have one of their ends sewed or otherwise fastened to the inner side of each of the spring-loops B. The other or detached ends of the said portions of webbing, C C, are then passed along the line and across the diameter in opposite directions, on opposite sides of the spring A, and are then passed in and through the opposite loop, B, after which they are suitably attached to or connected with the suspender proper, as seen in fig. 1.

On the under side of the suspender, is a piece of strong tape, D, or its equivalent, which is sewed to one of the pieces of webbing C, passing over the outer side of one of the loops B, for the purpose of confining and limiting the motions of the spring A.

The above is only one of the modes in which my metallic elastic attachment may be constructed. It may be modified in a great many ways, all of which would, however, involve the same principle, and I do, therefore, not confine myself to the peculiar construction of the spring, nor to the manner above described for attaching the same to a suspender or other article where needed.

I will now mention a few of the ways in which my attachment may be modified.

One of the portions of webbing C, after being secured to the spring-loop B, may be passed alternately under and over the cross-arms or sections of the spring A, or, as it were, woven in or passed through the centre cavity of the several folds of said spring its whole

length, and thence out through the opposite loop, as in the former case.

I may use a series of springs, wound in a slight oval zigzag form, or small spiral springs, having each two fine wires or cords passing through the centre of the cavity of their coils, one end of each of said wires being fastened to the opposite end of the spring, and the other ends fastened to a loop or buckle.

The spring A may be so formed that its folds shall be close to each other when in its natural contracted position: The two webbing pieces C C are then placed one on each side of the spring, while the spring is held in a-stretched or extended position, and sewed together at their edges, in the centre, and intermediate space, which sewing closely and securely confines said spring, while in an extended condition, between the two pieces of webbing or other fabric, being in a natural condition. This spring is used by extension, which is limited by confinement of said fabric and sewing.

Both of the webs C C may be passed within or between the folds of the spring. Or there may be three webs used, one passing between the folds, one end being fastened to one end of the spring, and the other end passing through the centre of the loops or folds of said spring, and out of the loop at the other end of the spring. The other two webs are fastened on the two sides of the loop, at one end of the spring, and passing on the opposite sides of the spring, in the same direction, are sewed at their edges, forming a case, enveloping the said spring and centre web.

The spring A may be made of any suitable metal, with or without said loops or eyes B B.

The zigzag spring may be flat or of an oval wind, as desired, with pointed, square, or curved ends at their bends. One or more may be used at a time.

The connections C C may be made of ordinary suspender-webbing or tape, or other fabric, or of leather, or other like materials; also, of round or flat wires, or thin sheets of any metal, &c., proper to combine the said spring with the body of the suspender, shoulder-brace, &c., to cause it to operate as an elastic for said articles, instead of India rubber, as now used, by its drawing or pressing the the folds of the spring toward each other from opposite directions.

Having thus fully described my invention,

What I claim as new, and desire to secure by Letters Patent, is—

The combination of the spring A, straps C C, and tension-regulator D, all substantially as and for the purposes herein set forth.

In testimony that I claim the foregoing, I have hereunto set my hand, this 25th day of August, 1869.

Witnesses: CASPER VAN HOESEN.
